UNITED STATES PATENT OFFICE.

WILLIAM E. WOODARD, OF FOREST HILLS, NEW YORK.

LOCOMOTIVE.

Application filed July 22, 1922. Serial No. 576,782.

To all whom it may concern:

Be it known that I, WILLIAM E. WOODARD, a citizen of the United States, residing at Forest Hills, in the county of Queens and State of New York, have invented certain new and useful Improvements in Locomotives, of which the following is a specification.

This invention relates to improvements in locomotives, and its nature and objects and advantages will be, perhaps, best understood from a brief statement of present practice.

In the construction, almost universally used with locomotives having the fire box placed back of the driving wheels and having a trailer truck, the main frame extends through from the last driving wheels to the back end of the locomotive. The frame usually consists of two flat slabs of forged steel, or a steel casting in which foot plates and boiler supports, both front and rear are cast together with the side members. The trailer truck, usually of the two-wheel type, is pivotally connected to the main frame just back of the rear drivers and radomes underneath the rear extension of the frame or frame cradle, the superimposed weight being transmitted to the truck through means of sliding plates, rockers, or swing links. In this construction tractive force exerted by the locomotive engine is carried through the frame and foot plate attached thereto, and transmitted to the tender which follows the locomotive by means of a drawbar. It will be noted that in this construction the frame structure of the locomotive carries all of the tractive effort exerted by the locomotive engine and the trailing truck is purely a carrying truck. By reason of the rapid increase in size of locomotives and the weight thereof, certain well-defined limitations have become apparent in the construction just described, and these limitations present a serious handicap upon further development of the locomotive as a whole, as well as presenting difficulties in the design and operation of present types of locomotives.

Among these difficulties the following may be noted: The connection from the locomotive to the tender is necessarily at the extreme end of the frame extension above mentioned and it is evident that on curves the extreme back end of the engine, on account of its overhang, has a very large lateral motion relative to the center line of the

track, necessitating special construction of buffers and drawbars between the engine and the tender to allow for the excessive swing at the back of the engine. The swing often amounts to as much as 12" or 14" each side of the center line of the track, and it is at once apparent that there are difficulties encountered when it is necessary to provide and maintain a coupling between engine and tender suitable for transmitting the very heavy locomotive tractive power now used through a connection which is capable of a side motion as great as this.

It will also be noted that it is undesirable to transmit the heavy tractive power developed by the locomotive engine through a connection at the back of the engine which may have, at times, as much as 12" or 14" offset from the center line of the track.

Again, the size of the locomotives has grown to such a point that the trailer wheel loads are excessive, and one of the greatest difficulties the locomotive designer encounters is to keep these trailer truck weights within reasonable limits, this being particularly true since the introduction of the locomotive booster as an adjunct to the main locomotive engine, such booster being carried on the trailer truck frame.

In addition, the very construction of the frame itself and the necessity of providing rear frame extensions heavy enough to carry the tractive force of the locomotive and the provision of a truck of sufficient strength to carry the load, greatly reduces the space available for the ash pan under the fire box. The capacity of the ash pan and the size of the opening through the ash pan for the admission of air beneath the grate are important and vital elements in the operation of the locomotive boiler, and the limitation imposed by the element above mentioned constitute a serious handicap and limit upon further advance in locomotive design and upon proper operation of many of the locomotives as at present constructed.

The introduction of the locomotive booster has added further problems in that the booster must also be accommodated in the limited space at the back end of the locomotive underneath the fire box and frame extensions as at present designed. It is highly desirable to obtain a greater amount of space for the booster engine, but with present constructions it is practically impossible to secure any more space for this purpose.

and thus the size of such an auxiliary power unit is limited.

In such locomotives as are equipped with stoker mechanism, it will be seen that the 5 conditions above noted are rendered still more marked.

It is one of the primary objects of my invention to provide an improved form of locomotive of simple construction which 10 meets the difficulties above mentioned; and in which, also, a maximum space is made available underneath the fire box for the ash pan, the booster motor, stoking mechanism and other parts.

15 Another object of my invention is to provide an improved form of articulated frame construction in which the frame portions, in effect, operate as a unitary structure, vertically considered, while there is freedom 20 for swinging or lateral movement of that portion of the frame which is beneath the fire box. More specific objects and advantages will appear hereinafter in the description of the invention.

25 I accomplish the foregoing, together with such other objects and advantages as may be incident to my invention by means of a construction which I have illustrated in preferred form in the accompanying drawings, wherein:

30 Fig. 1 is a fragmentary side elevation of the rear portion of a locomotive illustrating the application of my improvements thereto; Fig. 2 is an end elevation of Fig. 1; Fig. 35 3 is a section taken on the line 3—3 of Fig. 1; Fig. 4 is a plan view of Fig. 1 with the fire box and boiler removed; and Fig. 5 is a diagrammatic view illustrating a modification 40 of my invention.

45 Referring now to Fig. 1, it will be seen that I have shown only a portion of the boiler 7 and the fire box 8, both being of standard construction. The frame, however, is of divided construction and comprises a main portion A extending from a point approximately beneath the front end of the fire box forwardly underneath the boiler, and a supplemental frame B, the forward end of which is articulated with the 50 rear end of the main frame, as by means of the pivotal or hinge pin connection 9 which permits the supplemental frame to swing laterally with respect to the main frame during curving.

55 The main frame may be of standard construction comprising two side plates 10, connected together at front and rear by means of the cross ties 11. This frame has pedestals 12 to receive the boxes (not shown) for the drivers 13.

60 The articulated supplemental frame B comprises the side members 14, the forward cross member 15 and the foot plate 16 at the rear, all of the parts being preferably made integral. The side members 14 of the sup-

plemental frame have pedestals 17 for the journal boxes (not shown) in which the pair of axles 18, with which the frame is preferably provided, are journaled. The supplemental frame is outside the plane of its 70 wheels, and the side members are in the plane of the axle journals. The foot plate 16 is provided with a drawbar pocket 19 which, it will be seen on inspection of

Fig. 1, is located at the upper, rear 75 end of the frame; and it is also provided at its lower rear portion with a removable cradle-like cross member 20, serving as a support for the booster motor, indicated as a whole by the reference letter C. 80

The booster motor, if used, is also in part supported on suitable bearings on the rear axle of the supplemental frame in a manner well understood in this art, and extends rearwardly from such axle and through the 85 space between the cradle 20 and the foot plate. It will be noted that the construction in so far as thus described, is one by virtue of which maximum clearance spaces

are made available, both transversely and longitudinally of the supplemental frame, i. e., of the fire box. Transversely considered, the distance between the side members 14 of the articulated frame may be much greater than would be the case if the main 90

frame 10 were carried through to the back end of the locomotive as is the customary practice, and thus an ash pan of maximum width can be employed. Longitudinally considered, the pair of axles 18 of the supplemental frame can be widely spaced apart, irrespective of whether a booster is used or not, and thus maximum clearance between the axles is made possible for the ash pan. 95

Further ash pan clearance may be made possible by having one pair of the wheels supporting the supplemental frame of smaller diameter than the other, as shown in Fig. 5. If a booster is applied, it is preferable to make the leading wheels smaller in diameter 100 than the rear wheels of the supplemental frame.

The main frame A is connected to the boiler, in front and rear, in the usual manner, an expansion bearer 21 being shown at the rear, between the mud ring 22 of the fire box and the cross tie 11 of the main frame—the imposed weight is transmitted through the usual springs 23 and spring hangers 24.

115 The imposed weight may be transmitted to the articulated frame in any desired manner, but I prefer the arrangement shown, in which I provide fulcrums 24' on the cross tie at the rear of the main frame A for the equalizing beams 25 connected by hangers 26 to the forward end of the springs 27, the other ends of said springs being connected by the hangers 28 to an end of the beams 29

120 125 130 integral. The side members 14 of the sup-fulcrumed on the side members 14 of the

supplemental frame. The rearward ends of the beams 29 are connected by hangers 30 to the forward end of the springs 31. A pair of bearer supports 32 are placed at the rear of the fire box, one at either side, and weight is transmitted through these to the rear ends of the springs 31 through means such as the sliding shoes 33. Where a booster is used, it may be preferable to transmit a greater proportion of the weight to the wheels of the driven axle, to accomplish which I have made the fulcrum points 34 of the beams 29 nearer one end than the other, as will be seen on inspection of Fig. 1.

In order to provide a suitable support for the cab deck, cab stoker mechanism and other parts at the back end of the locomotive (heretofore carried on the rear extensions of the frame), I provide a supporting means preferably carried on the mud ring of the fire box. In the embodiment shown, this supporting means comprises a pair of members D which extend along the sides of the mud ring 22 for a substantial distance with their rear ends projecting beyond the back head of the box. They are secured at a plurality of points to an extension 22' of the mud ring as by the bolts or rivets 35. The members D where they extend along the mud ring, have an inwardly projecting, inclined flange 36 at their bottom, serving as a support for the ash pan 37; and they are also provided with an outwardly extending, curved flanged portion 38 which lends strength and rigidity and makes it possible to provide openings 39 in the vertical portion 40 of such members of a size such as will admit sufficient air into the fire box for proper combustion. Those portions of the members D extending rearwardly of the back end of the fire box are of channel shape and are connected by means of the cross tie or angle 41, and serve as a support for the cab deck 42 and cab 43. The bearer members 32 previously mentioned, may form a part of a cross member 32' and are riveted to the respective members D. The member 32' constitutes a support for the stoker mechanism diagrammatically indicated at 44 in Fig. 1. Thus all of the parts of the locomotive which are connected to and go with the boiler and fire box are supported by the members D and are thereby kept in fixed relation to the back end of the boiler.

The rear or tail portion of the main frame is provided with tongue-like projections 45, preferably two in number, such projections being adapted to extend into recesses 46 formed in the cross tie 15 of the supplemental frame. The recesses 46 have greater width than the projections 45 so that the supplemental frame will have freedom for radial movement about the pin 9 as a center, but the projections 45 are adapted to seat on the bottom or seat portions 47 of the recesses 46 and they thus perform two functions; namely, they assist and cooperate with the members 32 in maintaining the supplemental frame in horizontal alignment with the main frame (i. e., as against vertical displacement) and they serve to transmit weight from the main frame to the supplemental frame in such cases as where the main drivers pass over a low portion in the rails, such as at a joint. Thus, vertically considered, the two frames act as a unitary structure with freedom, however, of the supplemental frame to swing laterally with respect to the main frame during curving. This is of great practical utility because the equalizer work of the main frame is coupled to the equalizer work of the supplemental frame and the functioning of the equalizing means considered as a whole would be materially impaired if the two frames were not in effect unitary, vertically considered. The horns or projections 45 also prevent the front end of the supplemental frame from "kicking up."

I claim:

1. In a steam locomotive the combination of a main frame primarily supporting the superstructure, wheels supporting said frame, a supplemental frame articulated to the main frame for the transmission of pulling stresses, a pair of axles journalled in said supplemental frame and provided with wheels, and a booster motor carried on the supplemental frame for driving the wheels of an axle of such frame.
2. In a locomotive the combination of a main frame, wheels supporting said frame, a supplemental frame articulated to the main frame, a pair of axles journalled in said supplemental frame and provided with wheels, and a booster motor carried on the supplemental frame for driving the wheels of the rear axle of such frame, said motor being also supported on such rear axle and extending rearwardly therefrom.
3. In a locomotive the combination of a main frame, wheels supporting said frame, a supplemental frame articulated to the main frame, a pair of axles journalled in said supplemental frame and provided with wheels, and a booster motor carried on the supplemental frame, for driving the wheels of an axle of such frame, together with means for effecting distribution of imposed weight arranged so as to transmit more weight on said axle than on the other axle of the supplemental frame.
4. In a locomotive the combination of a main frame, wheels supporting the frame, a supplemental frame articulated to and extending rearwardly of the main frame, a boiler on the main frame having a fire box extending rearwardly over the supplemental frame, a pair of spaced axles having wheels for supporting the supplemental

frame, and an ash pan for the bottom of the fire box extending downwardly between the axles on the supplemental frame.

5. In a locomotive the combination of a main frame, wheels supporting the frame, a supplemental frame articulated to the main frame, a boiler on the main frame having a fire box extending rearwardly over the supplemental frame, a pair of spaced axles having wheels for supporting the supplemental frame, and an ash pan for the bottom of the fire box extending downwardly between the axles on the supplemental frame together with a booster motor for driving the rear axle of the supplemental frame extending rearwardly therefrom.

6. In a locomotive the combination of a main frame, wheels supporting the frame, a supplemental frame articulated to the main frame, a boiler on the main frame having a fire box extending rearwardly over the supplemental frame, a pair of spaced axles having wheels for supporting the supplemental frame, and an ash pan for the bottom of the fire box extending downwardly between the axles on the supplemental frame together with draft means at the rear of the supplemental frame and a booster motor for driving the rear axle thereof extending rearwardly from the said axle below said draft means.

7. In a locomotive the combination of a main frame, wheels supporting the frame, a supplemental frame articulated to and extending rearwardly of the main frame, a boiler on the main frame having a fire box extending rearwardly over the supplemental frame, a pair of spaced axles having wheels for supporting the supplemental frame, and an ash pan for the bottom of the fire box extending downwardly between the axles on the supplemental frame, one set of wheels of the supplemental frame being of smaller diameter than the other wheels.

45 8. In a steam locomotive the combination of a main frame primarily supporting the superstructure and its supporting wheels, a supplemental frame extending rearwardly of and articulated to the main frame, a pair of axles in said supplemental frame provided with wheels, and means whereby a greater portion of the imposed weight on said supplemental frame is transmitted to one pair of its wheels.

55 9. In a steam locomotive the combination of a main frame primarily supporting the superstructure and its supporting wheels, a supplemental frame extending rearwardly of and articulated to the main frame, a pair of axles in said supplemental frame provided with wheels, and means whereby a greater portion of the imposed weight on said frame is transmitted to one pair of its wheels, together with a booster motor for driving said pair of wheels.

10. In a locomotive the combination of a main frame and its supporting wheels, a supplemental frame, articulated to the main frame, a pair of axles in said supplemental frame provided with wheels, and means whereby a greater portion of the imposed weight on said supplemental frame is transmitted to one pair of its wheels, together with a booster motor for driving said pair of wheels in part supported on the supplemental frame and in part on the axle of said pair of wheels.

11. In a locomotive the combination of a main frame and its supporting wheels, a supplemental frame articulated to the main frame, provided with draft means at its upper rear portion and with a booster motor support on its lower rear portion, an axle in said supplemental frame provided with wheels, and a booster motor in part supported on said axle and in part on said support and extending between the support and the draft means.

12. In a locomotive the combination of a main frame and its supporting wheels, a supplemental frame articulated to the main frame and provided with pedestals, an axle and wheels for the supplemental frame, a cradle-like booster motor support on the lower portion of the supplemental frame to the side of the pedestals, and a booster motor carried on said axle and resting in the cradle.

13. In a locomotive the combination of a main frame and its supporting wheels, a supplemental frame articulated to and extending rearwardly of the main frame, and an axle and wheels for the supplemental frame adapted to be driven, said supplemental frame being provided with a booster motor support.

14. In a locomotive the combination of a main frame primarily supporting the superstructure and its supporting wheels, a supplemental frame articulated to and extending rearwardly of the main frame and provided with wheels and pedestals, said supplemental frame hinged to the main frame for radial movement with respect thereto, and interengaging means between the two frames substantially maintaining horizontal alignment therebetween but permitting radial movement.

15. In a locomotive the combination of a main frame primarily supporting the superstructure and its supporting wheels, a supplemental frame articulated to and extending rearwardly of the main frame and provided with wheels and pedestals, said supplemental frame hinged to the main frame for radial movement with respect thereto, and interengaging means between the two frames substantially maintaining vertical alignment therebetween but permitting radial movement, said means including a

tongue and a recess in which the tongue extends.

16. In a locomotive the combination of a main frame primarily supporting the superstructure and its supporting wheels, a supplemental frame articulated to and extending rearwardly of the main frame and provided with wheels and pedestals, said supplemental frame hinged to the main frame 10 for radial movement with respect thereto, and means at the forward and also at the rear portion of the supplemental frame affording support against horizontal disalignment but permitting radial movement.
17. In a locomotive the combination of a main frame primarily supporting the superstructure and its supporting wheels, a supplemental frame extending rearwardly of and articulated to the main frame, supporting wheels therefor, and means whereby more of the imposed weight may be transmitted on certain of the wheels than on others.
18. In a locomotive, the combination of a main frame primarily supporting the superstructure and its supporting wheels, a supplemental frame and its supporting wheels, said frame extending rearwardly of and articulated to the main frame and having lateral movement with respect to the main frame, and means whereby weight may be transmitted by the main to the supplemental frame.
19. In a locomotive, the combination of a main frame primarily supporting the superstructure and its supporting wheels, a supplemental frame and its supporting wheels, said frame extending rearwardly of and articulated to the main frame and having lateral movement with respect to the main frame, equalizing means for distributing imposed weight, and means whereby weight may be transmitted by the main to the supplemental frame.
20. In a locomotive, the combination of a main frame primarily supporting the superstructure and its supporting wheels, a supplemental frame and its supporting wheels, said frame extending rearwardly of and articulated to the main frame and having lateral movement with respect to the main frame, and means whereby weight may be transmitted by the main to the supplemental frame.
21. In a locomotive, the combination of a main frame primarily supporting the superstructure and its wheels, and a supplemental frame and its wheels, the supplemental frame being articulated to and extending rearwardly of the main frame and having its pulling members entirely outside the plane of its wheels.
22. In a locomotive, the combination of a main frame primarily supporting the superstructure and its wheels, and a supplemental frame and its wheels, the supplemental frame being articulated to and extending rearwardly of the main frame and having its pulling members entirely outside the plane of its wheels and in the plane of its journals.
23. In a steam locomotive, the combination of main drivers and a plurality of trailer axles with their wheels, and means whereby a greater portion of the imposed weight on the trailers may be transmitted to the wheels of one trailer axle, together with a booster for said last axle.
24. A steam locomotive having in combination a boiler and fire box, a main driving frame primarily supporting the superstructure, main driving wheels, a plurality of axles with their wheels, and a frame under the box in which said plurality of axles are journaled, said last-mentioned frame being articulated with the main frame and transmitting pulling strains and having its longitudinal pulling members entirely outside the plane of the wheels.
25. In a locomotive, a main frame primarily supporting the superstructure, a weight supporting, supplemental frame adapted to extend rearwardly of and to be articulated with the main frame, said supplemental frame comprising side and end members, the side members having a plurality of pairs of pedestal jaws, the forward end member having means for articulation with the main frame and the rearward end member having a draft pocket therein, all cast integral.

In testimony whereof, I have hereunto signed my name.

WILLIAM E. WOODARD.
